UNITED STATES PATENT OFFICE.

HENRY F. DOBBIN, OF NEW YORK, N. Y., ASSIGNOR TO WESTERN ELECTRIC COMPANY, INCORPORATED, OF NEW YORK, N. Y., A CORPORATION OF NEW YORK.

COORDINATE SWITCH.

Application filed May 4, 1922. Serial No. 558,546.

To all whom it may concern:

Be it known that I, HENRY F. DOBBIN, a citizen of the United States, residing at New York, in the county of New York,

5 State of New York, have invented certain new and useful Improvements in Coordinate Switches, of which the following is a full, clear, concise, and exact description.

This invention relates to automatic 10 switching apparatus and more particularly to coordinate switches of the type used for establishing connections in an automatic telephone exchange system.

The present invention is an improvement 15 on the switch structure of the type generally disclosed and described in the British Patent 183,436 issued to Western Electric Company, Limited, accepted August 23, 1923, which is directed to a switch structure 20 having camming members, or cards for moving sets of active contacts into engagement with sets of passive contacts, the camming cards being mounted on resilient supports and arranged to be moved through the 25 joint operation of actuating bars.

The object of this invention, therefore, is to provide an improved form of switch structure of the character above described which will be simple, economical and reliable in operation.

30 A feature of the invention consists in the combination of normally disengaged contacts, operating members or cards for effecting the engagement of the contacts, and a 35 selective mechanism for operating said cards, with members for guiding the cards, so that the engagement of the contacts may be accomplished in a positive manner.

Other features and advantages of the 40 invention will appear from the following detailed description and the claims appended hereto, reference being had to the accompanying drawings, in which Fig. 1 is a partial front assembly view of said switch; Fig. 2 is a cross section view thereof; Fig. 3 is a right-hand side view of Fig. 1 showing the middle set of contacts in operated position; Fig. 4 is a detail sectional view of a 45 guide showing a set of contacts, and a camming card in position in the guide.

The sets of passive conductors 1, 2, 3 and 4, etc. are securely fastened at their ends to fixed members (not shown) forming a portion of the supporting frame 5 of the switch

(Fig. 3) and are preferably woven in and 55 out between insulating strips 6 in the manner disclosed in the aforementioned application.

A support 7 of insulating material, also 60 suitably secured to the frame of the switch, is provided for each row of sets of flexible wire contact springs or active conductors 8, 9, 10, 11, etc. These supports 7 are disposed 65 at right angles relative to the direction of the length of the grid conductors 1, 2, 3 and 4. The free ends of each set of contact springs 8, 9, 10 and 11 extend through oblique apertures 12 in a camming member or card 13, each of said cards being slidably arranged in a channel-shaped guide 14 consisting essentially of a plate 15 and strips 16 overlying opposite edges of said cards. The card 13 is normally arranged in the guide to hold the active conductors 8, 9, 10 and 11 70 out of contact with the grid conductors 1, 2, 3 and 4 by means of a resilient support 17 which is adjusted normally to rest in the bottom of a V-shaped aperture 18 of the plate 15.

The specific form of selective mechanism 40 shown and described herein does not form a part of this invention but is described and claimed in the British Patent 213,437, issued to the Western Electric Company, Limited, accepted April 3, 1924. The above mentioned mechanism comprises generally a plurality of selective bars 19, each being associated with a row of sets of active conductors. The said bar 19 carries a plurality of cams 20 and is journaled at its end portions 85 90 in suitable bearings not shown. Securely attached to each bar is an arm 21, arranged to be operated by an arm 22 carried by the armature 23 of electromagnet 24.

Associated with each set of grid conductors is a bar 25 which carries a plurality of resilient operating arms 26, each of which is associated with a cam 20 of the vertical bars 19 with which bar 25 cooperates. The arms 26 are adapted to be engaged by the 95 100 cams 20 upon conjoint operation of the respective bars 19 and 25. The said bar 25 is journaled at its end portion in bearings not shown. Securely attached to each bar 25 is an armature 28 which is arranged to be 105 attracted by electromagnet 27 whereby the bar is rotated through a small angular distance. The selective bars 19, together with

their cams, are likewise rotatable in response to the energization of electromagnet 24, one of which is provided for each bar.

What is claimed is:

5. 1. In a switching mechanism, a set of contacts, an operating member for said contacts, means for guiding said member including a plate, said contacts extending through an aperture in said plate, and means on said plate arranged to form a channel in which said member is retained.
10. 2. In a switching mechanism, sets of contacts, an operating member for each set of said contacts, means for guiding said members including a back supporting plate, a plurality of strips on said plate, said strips by cooperation with said plate forming a channel-shaped guide for said members, and means for operating said members in said guide.
15. 3. In a switching mechanism, sets of contacts, a tie member individual to each of said sets, and means for guiding said members including a plate, said contacts extending through an aperture in said plate, a plurality of strips on said plate, said strips having portions extending partly over the front of said member whereby said member is retained but free to slide in said guide.
20. 4. In a switching mechanism, a set of passive contacts, a set of active contacts normally out of engagement therewith, a tie member for said active contacts, a flexible support for said tie member, a channel-shaped guide member, and means for operating said support to move said tie member in the channel-shaped guide to effect contact between said passive and active contacts.
25. 5. In a switching mechanism, a plurality of sets of passive contacts, a plurality of sets of active contacts normally out of engagement therewith and arranged in coordinate rows with respect to the first mentioned sets, a tie member for each set of

said active contacts, a flexible support for each of said ties, means for guiding said ties including a plate, a plurality of strips mounted on said plate and arranged to co-operate therewith to form a channel-shaped guide in which said tie members are free to slide, and means for selectively moving said members individually in said guide to effect interengagement between said contact sets.

50. 6. In a switching system, a plurality of sets of contacts, operating members therefor arranged in rows, a mounting plate, and strips secured to said mounting plate in a manner to form a guide for each row of members, each strip being arranged to form a portion of a guide for more than one row of said members.

60. 7. In a switching system, a plurality of sets of contacts, operating members therefor, a mounting plate, and strips secured to said mounting plate in a manner to form a guide for each member, each strip being disposed so as to form a portion of a guide for more than one of said members.

65. 8. In a switching system, a plurality of sets of contacts, operating members therefor, a mounting plate, and strips secured to said mounting plate in a manner to form a retaining guide for each member, each strip being disposed so as to form a portion of a guide for more than one member.

70. 9. In a switching device, the combination of sets of active contacts arranged in rows, sets of grid wire contacts associated with said active contacts, an operating card for each set of said active contacts, resilient supports for said cards, a plate disposed in a plane parallel to and adjacent to said grid wire contacts, and V-shaped apertures in said plate for holding each of said supports in adjusted position to permit the mounting or removal of said grid wire as a unit without obstruction from said active contacts.

75. In witness whereof, I hereunto subscribe my name this 1st day of May A. D., 1922.

HENRY F. DOBBIN.
